UNITED STATES PATENT OFFICE.

JOHN C. CORAM, OF LOWELL, MASSACHUSETTS.

RECEPTACLE MADE OF PAPER AND SIMILAR SHEET MATERIAL.

1,030,163.

Specification of Letters Patent. Patented June 18, 1912.

Application filed January 24, 1912. Serial No. 673,145.

To all whom it may concern:

Be it known that I, JOHN C. CORAM, a citizen of the United States, residing at Lowell, in the county of Middlesex and 5 Commonwealth of Massachusetts, have invented a certain new and useful Improvement in Receptacles Made of Paper and Similar Sheet Material, of which the following is a specification.

10 This invention relates to receptacles made of paper and similar sheet material and it is especially applicable to the making of cuspidors, which may be used for a short time and then destroyed with their contents 15 by fire.

The object of the invention is to furnish a very cheap and sufficiently durable receptacle in which the body is formed of a single strip of sheet material in such a manner 20 that the overlapping courses of the strip will make the walls of at least double thickness and sufficiently stiff. In forming the body of the receptacle or vessel in this manner, there is little or no waste in the paper 25 from which the vessel can be made, the paper coming from the paper mill in the form of a roll with parallel edges. While the body of the vessel is damp, that is, before the adhesive material used to unite the 30 courses of the strip is set a groove or crease may be formed on the inside of the body to receive the bottom which is represented as circular. The vessel after being made 35 will preferably be treated with a coating of waterproof liquid which may also be not fire-proof but fire resisting to a considerable extent. While such receptacles are adapted for many uses this invention is principally intended to supply cuspidors 40 for mills and factories or other places where large numbers of people are gathered, at a price so low that the cuspidor can be burned as cheaply as an ordinary cuspidor 45 could be cleaned.

5 In the accompanying drawing, Figure 1 is a plan of a receptacle suitable for a cuspidor constructed according to my invention; Fig. 2, a side elevation of the same; Fig. 3, a central vertical section of a part 10 of such a cuspidor showing the construction; Fig. 4, similar to Fig. 3, but showing a slight modification to support a cover.

The body A of the vessel is of the shape 5 of the frustum of an inverted cone and is formed from a strip a having parallel edges

which strip is first wound at the bottom of the body, so that the second course surrounds the first course to form a ring a¹, adapted to support the bottom B which is represented as a disk of as large diameter 60 as the first two courses of the strip a. After forming the first one or more annular courses, the strip is wound conically and spirally in such a manner that each course overlaps the preceding course, preferably, 65 about half the width of the strip, until a sufficient depth of body is secured and the last course is wound in an annulus a² or ring one or more times, partly to improve the appearance of the vessel and partly to stiffen the 70 rim or upper edge of the vessel. It will be understood that suitable adhesive material will be applied to the overlapping parts of the strip before or during the winding of the strip and that the edges of the bottom 75 B on the underside are also covered with adhesive material before the bottom is placed upon the top of the first one or more parallel courses. Ordinarily the adhesive 80 material will be sufficient to retain the bottom in place but for greater security the body may be creased on the inside at the top of the parallel course before the body has become too dry, to receive the edges of 85 the bottom, as indicated at c in Fig. 3.

After the vessel is formed it will be treated to some suitable water proofing material, as by dipping or other convenient methods in a liquid adapted to dry upon the vessel and form a coating thereon. Melted 90 paraffin may be used for this purpose, but it is desirable that the water proofing material should be of such a nature as not readily to catch fire from a burning match 95 carelessly thrown therein.

Fig. 3 shows a plurality of annular courses next to the double course at the top to form a ledge a³ to support a cover D which may be secured in place by bending the top inward over the edge of said cover, 100 as by burnishing, that is, by pressing a smooth hard surface against the outside of the top while the receptacle is being revolved about its axis.

I claim as my invention:

1. A vessel having an upwardly flaring body formed of a single strip of sheet material of uniform width wound at the bottom in one or more parallel annular courses and above said annular courses wound in spiral 110

overlapping courses secured to each other by adhesive material and having a bottom resting on said annular course or courses.

2. A vessel having an upwardly flaring

5 body formed of a single strip of sheet material of uniform width wound at the bottom in one or more parallel annular courses and above said annular courses wound in spiral overlapping courses secured to each other 10 by adhesive material and having a bottom

resting on said annular courses and having an annular crease at the top of said annular courses to receive the margin of said bottom.

In witness whereof, I have affixed my 15 signature in presence of two witnesses.

JOHN C. CORAM.

Witnesses:

ALBERT M. MOORE,

WILLIAM F. CURTIN.
